POLE TREE PRUNERS

Robert Schwabl, Jr., Ramsey, N. J.

Application November 25, 1936, Serial No. 112,794

2 Claims. (Cl. 30—185)

This invention relates to a pruning tool or device primarily adapted for cutting limbs and trimming trees.

It is particularly aimed to provide a novel construction which is more powerful than existing ones due to double leverage action attained thereby and the utilization of gravity by having the cutting action occur from the top downwardly to eliminate a portion of the resistance in cutting a limb, which will ease up the cutting of the remainder of the limb by its own weight.

The invention also resides in the novel details, combinations and arrangement of the parts.

Various additional objects and advantages will become apparent from a consideration of the description following taken in connection with accompanying drawing illustrating an operative embodiment.

In said drawing:—

Figure 1 is a view of the improved apparatus in side elevation;

Figure 2 is a vertical sectional view through the apparatus with one of the side members removed;

Figure 3 is a cross sectional view taken on the line 3—3 of Figure 1, and

Figure 4 is a vertical sectional view taken on the line 4—4 of Figure 1.

Referring specifically to the drawing wherein like reference characters designate like or similar parts, the invention embodies two side members or plates designated 10, which are secured rigidly together in spaced relation by means of a multiplicity of rivets as at 11. The plates are adapted to be carried by a pole or staff 12 and are secured thereto by bolts or rivets 13 passing therethrough and through openings in shanks 14 of said plates 10. At the upper ends of the plates, they terminate in similar forwardly extending hooks 15 whose bills extend downwardly and between which a cutter blade 16 is disposed, preferably removably by bolts or the like 17 passing through openings therein and through openings in the plates 10 adjacent the hooks. The cutting edge of the blade 16 is lowermost as at 18 and it bridges the throat or space of the hooks.

Co-acting with the blade 16 is a vertically slidable jaw 19 having a projecting portion 20, so that a limb to be cut will be engaged between the cutting edge 18 and the projection 20. Said jaw has a vertical slot 21 through which a bolt or rivet 22 passes. The jaw has an upwardly extending projection 23 thereon which is disposed between two of the rivets 11. The projection 23 and associated rivets 11 and the slot 21 and bolt 22, effectively guide the jaw 20 for vertical movement.

Gear or rack teeth are provided as at 24 on the jaw 19 which are enmeshed with teeth 25 of a lever or segment 26 pivoted by a bolt or rivet 27 to and between the plates 10. A pitman 28 is pivoted at 29 to the lever 26 and at 30 to a lever 31

in turn pivoted at 32 to a bracket 33 fastened to the pole or staff 12. Lever 31 is urged upwardly through the action of a contractile coil spring 34 fastened thereto and also fastened to an eyelet 35 secured to the staff or pole 12. The lever 31 has an actuating rope 36 depending therefrom at the free end.

In the use of the device, the limb or part to be severed is engaged between the cutting edge 18 and the projection 20 of jaw 19. Thereupon operating element 36 is pulled downwardly moving therewith the pitman 28 and rocking the lever 26 which through the interengagement of the gear teeth at 24 and 25, moves the jaw 19 upwardly with great power. The cutting of the limb is in a downward direction. The power is augmented by the novel gearing and the device utilizes the action of gravity by having the cutting action take place from the top down since it eliminates one-half of the resistance in cutting the limb which will ease up the cutting of the other half by its own weight.

Various changes may be resorted to provided they fall within the spirit and scope of the invention.

I claim as my invention:—

1. A pruning tool of the class described comprising a pair of initially separate plates, a multiplicity of rivets securing the plates together in spaced relation, said plates at the upper end having forwardly extending hooks open at the lower portions thereof, a cutter member secured between said hooks by certain of said rivets with its cutting edge lowermost and bridging the throat of the hooks, a jaw below the cutting edge slidably disposed for vertical movement between the plates, certain of said rivets positioning and guiding the jaw, lever means pivoted to the plates and geared to the jaw, a pole extending from the plates, and operating means for said lever means.

2. A pruning tool of the class described comprising a pair of initially separate plates, a multiplicity of rivets securing the plates together in spaced relation, said plates at the upper end having forwardly extending hooks open at the lower portions thereof, a cutter member secured between said hooks by certain of said rivets with its cutting edge lowermost and bridging the throat of the hooks, a jaw below the cutting edge slidably disposed for vertical movement between the plates, the jaw having an elongated slot entered by one of the rivets and having an extension disposed between others of said rivets for positioning and guiding the jaw, a lever geared to the jaw, a pole extending from the plates, a lever pivoted to the pole, a pitman connecting the levers, and a contractile spring connected to the second lever and to the pole.
